UNITED STATES PATENT OFFICE

DAVID E. HUNTER, OF MUSKEGON, MICHIGAN, ASSIGNOR TO THE SHAW WALKER COMPANY, OF MUSKEGON, MICHIGAN, A CORPORATION OF MICHIGAN

EXTENSION TOP FOR DESKS AND THE LIKE

Application filed February 27, 1928. Serial No. 257,160.

This invention relates to improvements in extension tops for desks, and more particularly to a sliding top or shelf capable of being concealed beneath the permanent top when not in use, and to be withdrawn beyond one edge of said top and elevated into the plane thereof to provide an increased working area when required.

The object of the invention is to provide an extension or auxiliary top member which can be readily shifted to and from extended position, and when so extended not only presents a working surface flush with the surface of the permanent top but one which abuts edgewise thereagainst thus affording no break or interval between. Such an extension therefore possesses distinct advantages over the ordinary type of extension top common to desks, tables and the like, which are below the permanent top, and therefore while affording additional working area are not so positioned as to be the equivalent of an extension flush with the permanent top. Manifestly an extension top of the character hereinafter to be described is not limited in its use to any particular type of office equipment but to all types of desks, tables, counters, cabinets and like structures having a top surface.

A preferred embodiment of the invention is disclosed in the accompanying drawings, in which

Figure 1 is a top plan view of the portion of a desk top below which the extension top is located, portions of the permanent and extension tops being broken away to show the supporting carriage beneath,

Figure 2 is a view in vertical transverse section taken on line 2—2 of Figure 1.

Figure 3 is a view in longitudinal vertical section through the front edge portion of the desk taken on line 3—3 of Figure 2 showing the extension top in retracted position.

Figure 4 is a view similar to Figure 3 showing the top extended preparatory to elevation.

Figure 5 is a view similar to Figure 4 showing the top elevated into the final position.

Figure 6 is a detail view of one of the link connections between the top section and car-

riage of the extension top as taken on line 6—6 of Figure 1.

Figure 7 is a top plan view of one edge portion of a desk with extension top and guard rail in extended position.

Figure 8 is a view in side elevation of the extension top and guard rail in extended position.

Figure 9 is a view in front elevation of the extension top and guard rail in retracted position; and

Figure 10 is a perspective view of the same parts in partially extended position.

For the purpose of this disclosure, the upper portion of a metal desk is shown, including the permanent top and a space immediately below in which the extensible top is housed. According to the usual practice, the extension top is arranged to be withdrawn forwardly and into extended position at one or both sides of the desk, the left side being illustrated herein.

Referring now to the construction embodying the features of the invention, the upper section of the desk is provided with a relatively shallow housing over which extends the top wall 1, and surrounded on three sides by side walls 2, 2 and a rear wall 3, the front being open to provide an entrance slot for the extension top and from which the forward edge thereof projects. The top wall is preferably covered with a layer of linoleum 1a or other covering material which forms the top surface of the desk.

As is the practice in metal furniture construction, the frame members and walls of the desk are formed from blanks of sheet metal, shaped and spot-welded into a rigid structure but these details of construction need not be elaborated upon. Within the top casing is housed the extensible top, consisting of two main and relatively shiftable members, to wit, a carriage or sliding frame 4, and the top section 5. The carriage 4 is a flat skeleton frame member mounted on rollers to slide in a horizontal plane inwardly and outwardly. The top section 5 is a flat plate mounted upon and moving with its carriage, and capable of being shifted vertically and horizontally relative thereto by means

of intermediate connecting and operating parts whereby it can be elevated when the carriage has been extended forwardly into extended position to bring the surface of the top into the plane of the desk top and at the same time shifted rearwardly to bring the rear edge of the top section into abutting contact with the front edge of the permanent desk top. In other words, the carriage and top section are drawn forwardly as a unit until the latter clears the front edge of the desk top, and then the top is swung vertically and horizontally to final position. The elevating and depressing of the top section is accomplished manually by lever actuated mechanism which imparts a parallel movement to the top.

As shown in Figures 1 and 2, the carriage 4 consists of a pair of longitudinal frame members 6, 6, consisting of strips of sheet metal bent into substantially S-shape (thus). These frame members extend just below the side edges of the top section 5, and are connected together by three parallel transverse frame members 7, two being located at the ends of the carriage and one just forwardly of the rearmost member. These cross members are strips of sheet metal bent into inverted U-shape (thus), their ends being mortised and spot-welded to the longitudinal frame members 6, 6.

The transverse frame member 7 at the extreme rear of the carriage forms a housing for a pair of pintle rods 8, 8, held in place by bolts 8a, 8a, these rods projecting from opposite sides of the carriage and carrying rollers 9, 9, at their extremities. These rollers engage track members 10, 10, secured to the side walls 2, 2, of the desk and extending from the rear end of the extension top housing to a point just short of its forward end. These tracks are channel shape with roller engaging flanges projecting inwardly, the rollers 9, 9, being slightly less in diameter than the vertical distance between the flanges, both of which are engaged, depending on the position of the carriage and the distribution of the load.

Extending across the forward end of the extension top housing and forming the lower edges of the entrance slot thereto is a U-shaped frame member 11 forming a part of the desk. Adjacent the ends of this frame member and in alignment with the downwardly facing channel section 6a, 6a, of the longitudinal frame members 6, 6, are mounted stationary rollers 12, 12, journaled in suitable roller bearings 13, 13. These rollers support the forward portion of the carriage, engaging downwardly facing tracks formed by the channel sections 6a, 6a, of the longitudinal carriage frame members 6, 6.

The extension top section 5 consists of a flat wall 14 covered with a layer of linoleum

15 and otherwise resembling a rectangular section of the permanent desk top. The edges of the top wall 14 are preferably surrounded by downwardly extending flanges 14a.

As shown in Figures 1 and 3, the top section 5 is somewhat shorter than the carriage 4, its rear edge terminating just forwardly of the intermediate cross member 7 of the carriage some six or seven inches from the rear end thereof, although its forward edge projects perhaps two inches beyond the forward cross member 7 of the carriage.

The top section is mounted on the carriage by two separate pairs of connecting and operating members, one adjacent its rear end and the other adjacent its front edge and the members of each pair being located at opposite sides of the extension top assembly and comprising parts as follows: The rear pair of connecting members consists of links 16, 16, pivotally connected at one end to the carriage and at the other end to the top section through the medium of inverted U-shaped channel members 17 extending lengthwise of the underside of the top section and positioned just inwardly from and above the longitudinal frame members 6, 6, of the carriage and pintle pins 18 passing horizontally and transversely through the depending webs of said channel members. These pintle pins are free to turn on their axis, being fixed to one end of each of the links 16. A similar pivot mounting is provided for opposite ends of the links, there being provided along the inner edge portions of the longitudinal carriage frame members, 7, 7, angle strips 19 with up-standing flanges 19a spaced from the side of the channel portion 6a of said longitudinal frame members, and in holes therein another pair of pintle pins 20, 20, for the opposite ends of the links 16 are journaled.

The connecting members at the front of the top section also include the operating parts consisting of the following mechanism: Just rearwardly of the foremost cross member 7 of the carriage frame, is a transverse rod or crank shaft 21 journaled at its ends in the inner vertical walls of the channel portion 6a of the longitudinal frame members 6, 6, of the carriage frame (Figure 2). Fixed to the shaft 21 just inwardly from the journaled ends thereof, are cranks 22 positioned in vertical alignment with the channel members 17 on the under side of the top plate 14. At the ends of the crank arms are transverse pins 22a which are journaled in holes punched in the outer depending flanges of the channel member 17. Midway between the ends of the shaft 21, is fixed an operating lever 23 for turning the shaft 21 and cranks 22 and thus elevating and lowering the extension top as will now be described; reference being later made to the means employed for locking the operating lever to hold the top in elevated

position and for releasing the same for lowering the top.

As is readily apparent from the foregoing description, the position of the extension top when not in use, is within the space directly beneath the desk top, with its forward edge projecting a short distance from the entrance opening so that it can be conveniently withdrawn. In the retracted position of the extension top, its carriage 4 assumes a position with its rear end wall substantially abutting the rear wall 3 of the desk, with its rear set of rollers 9, 9, supported at the inner ends of the supporting tracks 10, 10 (Figure 1). To withdraw the top from the desk, it is merely pulled outwardly from the front edge, the carriage 4 and top 5 moving as a unit, partly supported by the rollers 9, 9, and partly by the stationary rollers 12, 12. When the top is extended to a position beyond the front edge of the desk top in which its rear edge clears the same by an inch or so, its further withdrawal is prevented by two stops 6b and 6b secured to the longitudinal frame members 6, 6, of the carriage and project downwardly for contact with the forward frame member 11 of the desk (Figure 3).

In the extended position (Figure 3) the top section 4 lies flatwise upon the carriage and in a depressed position, that is, with its surface below that of the desk and a space between the rear edge of the top and the front edge of the desk. Moreover, the operating lever 23 is in a position extending horizontally from the shaft 21 and in a rearward direction. The top section is elevated by reaching under the top, grasping the handle 23a at the end of the lever and pulling downwardly and forwardly thereon. By this movement the shaft 21 is rotated in a clockwise direction through 90°, at the same time rotating the cranks 22, 22, in a counter-clockwise direction (Figure 4) from a horizontal forwardly extending position to a vertical position. This movement of the cranks carries the top section 5 upwardly and rearwardly with a parallel movement, the links 16, 16, being the equivalents of the cranks, respond to the force imparted to the cranks, and also swing into a vertical position. This upward and rearward swinging movement of the top section thus simultaneously brings the surface of the top section into the plane of the desk top, and brings its rear edge into abutting engagement with the front edge of the desk top. In this connection it is to be observed that the parallel movement of the top section is due to equality of the throw of the cranks 21 and links 16, this throw in turn being equal to the radius of the arc through which the top is swung to bring it into and out of its elevated position.

The elevation of the top being a manual operation, additional means for holding the top in elevated position is required, since

otherwise it would return to its depressed position on the carriage when the lever is released. This means consists of locking members acting on the lever 23 to hold the shaft 21 against turning and comprises a link 24 pivotally connected to the lever 23 midway of its ends through the medium of a pin 25 passing through the link a short distance inwardly from its end and an ear 23b integral with the lever.

The link 24 extends rearwardly from the lever 23 and is connected for horizontal sliding movement at its opposite end with a channel member 26 mounted on the under side of the top wall 14 of the top section 5 approximately at its center and extending in a forward and rearward direction. In one of the depending flanges of the channel member 26 is a longitudinal slot 26a in which the adjacent end of the link 24 slides, a short pin 24a forming the connecting member. The length of the slot is such as to accommodate the travel of the pin 24a from end to end in the swinging movement of the operating lever 23 from the downward depending position shown in Figure 4 to the rearward horizontal position of Figure 3. At the forward end of the slot 26a is a downwardly offset locking notch 26b into which the pin 24a drops when carried forwardly by the downward swinging movement of the lever. In this position the link 24 assumes the function of a brace preventing the lever 23 from being moved in either direction and hence holding the top firmly in elevated position. To release the link 23 from the locking notch 26b so that the top can be lowered, the handle 23a of the lever is grasped as before and by pressing downwardly on the forwardly extending end of the link, its rear end is lifted sufficiently to release the pin 24a from the locking notch 26b thus permitting it to slide rearwardly in the slot 26a and the top to resume its depressed position on the carriage. Thus depressed, the carriage is free to be pushed backwardly into its retracted position within the desk.

In order to permit adjustment of the locking members to compensate for any slight variation in the assembly of the parts, the channel member 26 is not fixed directly to the underside of the top but indirectly through an angle plate 27 having one flange 27a spot welded to the wall 14, and the other depending in flatwise contact with unslotted flange of the channel member 26. Through these contacting flanges are inserted bolts 28, 28, the bolt holes in one of the flanges (preferably those in the fixed angle plate) being elongated so that the channel member 26 can be moved slightly forwardly or rearwardly and thus shift the position of the slot 26b as required.

As an added feature to be applied in conjunction with an extension top especially in a desk having vertically extending walls at the

back and one or both sides thereof, is a telescopic side rail adapted to form an extension of the fixed guard rail along the corresponding side of the desk.

A desk provided with guard rails and an extension or telescopic guard rail is shown in Figures 6 to 9. These guard rails 29 are merely vertical extensions of the side and rear walls projecting 2 or 3 inches above the top surface of the desk and are desirable in some forms of desks, as for instance for book-keeping or other special purposes to prevent papers from being dislodged and scattered. Otherwise the desk and the extension top are the same as already described. The extension rail 30 consists of a strip of sheet metal bent into L-section and slidably mounted in a housing located along the angle between the top of the desk and the side guard rail 29, and formed by mounting a housing plate 31 of a corresponding L-shaped section to the inner face of the guard rail, and housing plate having a marginal flange 31a along its top edge which is spot welded to the face of the guard rail with the main body of the plate slightly offset so as to form a space of the same general sectional contour of the extension guard rail 30 in which the latter can slide endwise with its horizontal web 30a flush with the surface of the desk. At the forward end of the extension guard rail 30 is a downwardly projecting pin 32 extending below the top of the desk and at one side of the top section 5 of the extension top. Fixed to the side edge of the top section is a bracket 33 having a vertical bore 33a therethrough and into which the pin extends for free vertical sliding movement. Thus as the extension top is withdrawn from the space beneath the desk top the extension rail is withdrawn from its housing above the desk top. During the forward movement of the extension top, the top section is below the level of the extension rail, but on being elevated, its side edge is brought up flush with the under side of the horizontal web 30a of said rail 30, the latter being curved downwardly at its edge to provide an edge-wise overlapping contact. Due to the sliding engagement of the pin 32 in the bracket 33, the top section is free to be shifted vertically relative to the rail as it is elevated or depressed and yet the connection is maintained so that they slide together to and from retracted positions in their respective housings. The advantages of an extension top embodying the features herein disclosed have already been pointed out, but otherwise would be obvious. Similarly the extension rail is a convenient addition to the extension top although not a necessary one. Structural details and mechanical parts may be obviously varied without departing from the spirit of the invention, and therefore I do not wish to be limited in either of these respects.

I claim as my invention:

1. An extensible top for desks and the like comprising a carriage slidably mounted in a space below the top of said desk for withdrawal to and from extended position, a top section mounted on said carriage and adapted to normally assume a position below and forwardly of the desk top in the extended position of said carriage, links connecting one end and cranks connecting the other end of said top section with said carriage, and a lever operatively connected with said cranks to rotate the same through a predetermined angle whereby said top section is swung upwardly and rearwardly from its position on said carriage when the latter is extended, to bring said top section into the plane of the desk top with its rear edge abutting the adjacent parallel edge of said desk top. 70 75 80

2. An extensible top for desks comprising a carriage slidable into and out of a space below the top of said desk, and having rollers adjacent its rear edge, tracks fixed to said desk along the sides of said space and engaged by said rollers, supporting rollers mounted on the desk below said carriage at the front 85 90 95 of said space and supporting said carriage, a top section mounted on said carriage for relative displacement, links connecting the rear portion of said top section with said carriage, cranks connecting the front portion of said top section with said carriage, a shaft journalled on said carriage and connected with said cranks, a lever mounted on said shaft, and locking means interposed between said lever and said top section. 100

3. An extensible top for desks comprising a carriage slidable into and out of a space below the top of said desk, and having rollers adjacent its rear edge, tracks fixed to said desk along the sides of said space and engaged by said rollers, rollers mounted adjacent the front of said space and supporting said carriage, a top section mounted on said carriage and normally resting in depressed position thereon below the level of the top of said desk with its rear edge spaced forwardly of the adjacent edge of said desk top when said carriage is extended, pairs of cranks and links journalled on said carriage and connected with the under side of said top section at 105 110 115 points spaced apart lengthwise thereof, a shaft connecting said cranks, a lever mounted on said shaft and operative to swing said cranks through a predetermined angle to effect the parallel motion of said top section into the plane of said desk top and in abutting contact at adjacent edges, a link pivotally connected at one end with said lever, a slotted member mounted on the underside of said top section and having slidable engagement with the other end of said link and a notch at one end of said slot adapted to prevent said link from sliding in the elevated position of said top section. 120 125 130

4. An extensible top for desks comprising

a carriage slidable into and out of a space below the top of said desk, a top section mounted on said carriage and normally resting in depressed position thereon below the level of the top of said desk, with its rear edge spaced forwardly of the adjacent edge of said desk top when said carriage is extended, pairs of cranks and links journalled on said carriage and connected with the under side of said top section at points spaced apart lengthwise thereof, a shaft connecting said cranks, a lever operatively connected with said cranks to swing the same through a predetermined angle to effect the parallel motion of said top section into the plane of said desk top and in abutting contact at adjacent edges, a link pivotally connected at one end with said lever, a guide member mounted on the underside of said top section and having a slot slidably engaged by the other end of said link and a notch at one end of said slot adapted to lock said link against sliding for locking said lever in the elevated position of said top section, and to be released therefrom to permit said top section to be depressed.

5. An extensible top for desks comprising a carriage slidable into and out of a space below the top of said desk, an extension top section mounted on said carriage for displacement relative thereto, links connecting said top section with said carriage, a crank member mounted on said carriage and connected with said top section, an operating lever connected with said crank member and coacting locking members on said top section and carriage and operative by said lever to lock said top section in extended and elevated position.

6. An extension top for desks and the like, comprising a carriage slidably mounted in a space beneath the top of the desk and extensible therefrom to a position outwardly beyond and below the level of said desk top, a top section mounted on said carriage for vertical displacement in its extended position into and from the plane of said desk, means for normally elevating said top section, and releasable means for supporting said top section in elevated position.

50 7. An extensible top for desks and the like, comprising a carriage mounted below the top of said desk for sliding movement to and from an extended position below and beyond one edge thereof, a top section supported upon said carriage, rocking members connecting said top section with said carriage including a hand actuated crank for shifting said top section vertically and horizontally into the plane of the desk top and into abutting contact at their edges, and means for locking said crank in the elevated position of said top section.

Signed at Muskegon this 23 day of February, 1928.

DAVID E. HUNTER.
